T. K. WOOD

CIGARETTE BUTT EXTINGUISHER

Filed Sept. 30, 1926

Inventor:—
Truman K. Wood.
By Martin P. Smith, Atty.

UNITED STATES PATENT OFFICE.

TRUMAN K. WOOD, OF LOS ANGELES, CALIFORNIA.

CIGARETTE-BUTT EXTINGUISHER.

Application filed September 30, 1926. Serial No. 138,600.

My invention relates to a cigarette butt extinguisher and has for its principal objects the provision of an ornamental device that combines with an ash tray or receptacle a plate or disk that is provided with a series of recesses or perforations that are adapted to receive the lighted ends of cigarette butts for the purpose of extinguishing the same and consequently preventing further smoke 5 from arising from the butt after it has been discarded.

A further object of my invention is to provide a cigarette butt extinguisher that is constructed so that the cigarette butts or 15 stubs placed in the extinguisher may be readily discharged therefrom into a receptacle that functions as an ash receiver.

Further objects of my invention are to provide a device of the character referred 20 to that is relatively simple in construction, inexpensive of manufacture, and of ornamental appearance.

With the foregoing and other objects in view, my invention consists in certain novel 25 features of construction and arrangement of parts that will hereinafter be more fully described and claimed and illustrated in the accompanying drawing, in which—

Fig. 1 is a perspective view of an ornamental object or fixture that includes my 30 improved cigarette butt extinguisher and an ash tray.

Fig. 2 is a plan view of the cigarette butt 35 extinguisher.

Fig. 3 is a cross section taken on the line 3—3 of Fig. 2.

Referring by numerals to the accompanying drawing which illustrates a practical embodiment of my invention, 10 designates 40 a tray or shallow receptacle, preferably circular in form, and which is adapted to function as an ash tray, and mounted on the edge of said tray and projecting upwardly therefrom is a standard 11, preferably a statuette, and supported by this figure or statuette and positioned directly over the central portion of the tray 10 is a disk 12 through which is formed a series of vertically arranged apertures 13, the diameters of 45 which are slightly greater than that of the average cigarette. The upper ends of the apertures 12 are preferably counter sunk as designated by 14 in order to facilitate the entrance of the lighted ends of the cigarette butts into said apertures.

Depending from the edge of the disk 12 is a pin or rivet 15, upon which is pivotally mounted a disk 16 that serves as a closure for the lower ends of the apertures 13 and this disk is mounted on its pivot pin so that 50 it may be turned to one side, thereby opening the lower ends of all of the apertures 13 so as to permit the cigarette butts and the ashes that have accumulated in the apertures 13 to discharge downwardly into the tray 65 or receptacle 10.

In the use of my improved extinguisher, the lighted end of the cigarette butt is inserted in one of the apertures 13 and the butt is forced downwardly in said aperture until the lighted end makes contact with plate 16. Inasmuch as the burning end of the stub can receive practically no air to support combustion, the fire will very quickly be smothered, thereby eliminating the objectionable 70 smoke that arises from smouldering cigarette butts.

By swinging plate 16 laterally in either direction so as to open the lower ends of the apertures 13, the cigarette butts that 75 have been placed in said apertures may be discharged into the tray or receptacle 10.

My improved device, and particularly the 80 perforated disk that receives the lighted cigarettes, cigars, and the like, may be constructed of any 85 suitable fire-proof material such as metal, glass, porcelain, or the like.

Thus it will be seen that I have provided a relatively simple, practical and convenient device for extinguishing the butts of 90 cigarettes, cigars, and the like, and which device is combined with an ash tray to provide an ornamental and convenient device.

It will be understood that minor changes 95 in the size, form and construction of the various parts of my improved cigarette butt extinguisher may be made and substituted for those herein shown and described without departing from the spirit of my invention, the scope of which is set forth in the 100 appended claims.

I claim as my invention:

1. A cigarette butt extinguisher comprising a disk provided with a series of perforations and a closure plate pivotally connected to the underside of said disk so as to swing in a horizontal plane and adapted when positioned directly beneath said disk to close the lower ends of all of the perforations in said disk. 105

2. In a device of the character described, a receptacle, a standard projecting upwardly from the side of said receptacle, a disk supported by said standard said disk being provided with a plurality of perforations and occupying a position directly above and over the center of said receptacle and a

plate pivotally mounted on the underside of said disk so as to swing in a horizontal plane in either direction and adapted when positioned directly beneath said disk to close the perforations therein.

In testimony whereof I affix my signature.
TRUMAN K. WOOD.
